UNITED STATES PATENT OFFICE.

ROBERT KUHN, OF CINCINNATI, OHIO.

TROLLEY-WHEEL.

SPECIFICATION forming part of Letters Patent No. 670,712, dated March 26, 1901.

Application filed November 10, 1900. Serial No. 36,058. (No model.)

To all whom it may concern:

Be it known that I, ROBERT KUHN, a citizen of the United States, and a resident of Cincinnati, Hamilton county, State of Ohio, have 5 invented certain new and useful Improvements in Trolley-Wheels; and I do hereby declare that the following is a description of the invention sufficiently clear, full, and exact to enable others skilled in the art to 10 to which it appertains to make and use the same, attention being called to the accompanying drawings, with the reference-numerals marked thereon, which form also a part of this specification.

15 The object of this invention is to protect the faces of trolley-wheels, the means used for the purpose being separable from other parts of the wheel, and therefore independently renewable, so that as long as this latter remains 20 otherwise in good condition it will not have to be discarded by reason of a worn-out rim or face.

These trolley-wheels wear rapidly at their rim, which travels in contact with the electric 25 conductor or wire, and they have to be replaced at frequent intervals on account of this excessive wear confined to a limited surface only, while all other parts remain yet in good condition. My invention removes this 30 objection and permits a trolley-wheel to be used much longer and until the same has become useless from general wear in all its parts.

In the following specification, and particularly pointed out in the claims at the end 35 thereof, is found a full description of this invention, its parts and construction, which latter is also illustrated in the accompanying drawings, in which—

Figure 1 is an edge view of a customary 40 trolley-wheel provided with the features of my invention. Fig. 2 is a side view of the preceding figure. Fig. 3 is a view similar to Fig. 1, the wire covering being shown in section and the construction for securing the 45 ends thereof being slightly modified. Fig. 4 is a side view of the preceding figure with parts broken away. Fig. 5 is a sectional detail view showing a modified form of my invention. Fig. 6 in a central cross-section

shows the construction of the wheel used in 50 connection with my invention.

In order to protect the grooved face of trolley-wheels, I provide a wearing-surface between the lateral flanges forming said groove of a material which forms an independent 55 part and is separable from the wheel-body, so that if worn out it may be removed from the latter and replaced by another. This wearing-surface is provided by covering said rim or face with one or more layers of wire, as 60 shown in the drawings. One layer I consider sufficient in most cases, which, with the bights resting against each other, is closely wound around the face of the wheel and may when worn out be renewed by simply rewinding the 65 wheel. The ends of the wire may be secured and held in various ways. As shown, I provide lugs 7, one at each side of the wheel, within perforations of which a wire end is held by a set-screw 8, or the end might be 70 knotted to prevent it from slipping through the opening in said lug. From the lug on one side the wire is then taken over the edge of the wheel, wound closely around the face of it, and secured to a similar lug on the other 75 side thereof. Wherever it passes around the edge of this latter it is desirable to provide a notch 9. In this case one continuous piece of wire would be used. Two pieces of wire may also be used, as shown in Figs. 3 and 4, 80 one end of each being started midway in the deepest part of the groove of the wheel. In such case these inner ends might be held within an opening 10 in the body of the wheel, the holding means—a wedge 11, for instance— 85 being applied from an opening through the side or from the bore of the hub, as shown in Fig. 4. The outer ends may be held as before described. There might also be a separate opening 10 for each wire end. The wire 90 ends may also be held by passing through a perforation 12 in the side or flange of the wheel near the outer edge thereof, as shown in Fig. 5. The wire may also rest in grooves 95 13, as shown in same figure. A trolley-wheel so protected may also be made much lighter than the ones at present constructed by casting, and the body thereof might be made of

sheet metal, as shown in Fig. 6, the various parts being formed to proper shape by stamping or otherwise.

Having described my invention, I claim as
5 new—

1. A trolley-wheel made of sheet metal formed to shape and having its face covered with a separable layer of wire.
2. A trolley-wheel having lateral flanges forming between them a groove around the face of said wheel, the sides of such groove

converging toward the deepest part of it and are wound with wire, the coils of which rest on said sides and also against each other, the higher ones upon the ones next below.

In testimony whereof I hereunto set my hand in the presence of two witnesses.

ROBERT KUHN.
